UNITED STATES PATENT OFFICE.

ALFRED LUBAC, OF PARIS, FRANCE.

PRINTING-TYPE-COMPOSING APPARATUS.

Application filed July 26, 1921. Serial No. 487,601.

To all whom it may concern:

Be it known that I, ALFRED LUBAC, a citizen of the Republic of France, and a resident of Paris, France, have invented certain new and useful Improvements in and Relating to Printing-Type-Composing Apparatus, of which the following is a specification.

The present invention has for its object a printing type composing or assembling apparatus in which the type is set up in lines by setting up machines or by the distributing apparatus.

Assembly of the type most frequently used is effected by means of a keyboard. The types which are seldom used are released by means of a push button comprising a small rod terminating in a small toothed disc of steel. If so desired these types may

be released by the fingers.

The type boxes are arranged in radial lines. When the types are in place they are unsupported at their ends and on account of their weight they are directed towards a collecting channel. In falling into the said channel the latter directs them in proper position. From the channel they debouche into the composing or assembling space from which they are pushed one after the other by a push lever actuated by to-and-fro movement by means of a cam wheel and a retracting spring.

In order that the invention may be clearly understood reference is made to the accompanying drawings which show by way of example a construction and arrangement in accordance with the present invention.

Fig. 1 is a plan view of an apparatus which during working is mounted on a base piece in such manner as to have an incline of 45°.

Figure 2, drawn to an enlarged scale, is a section on the line A—A Figure 1, showing the level of the collector which forms a continuation for the slide or chute of the first platform. In this view is also shown the level of the composing platform and the mouth of the slide or chute of the second platform.

Figure 3, drawn to an enlarged scale, is a section on the line B—B Figure 1, showing the level of the slide or chute for the spaces (which is the same as that for the collector) and the level of the composing or assembling platform.

Figure 4, drawn to an enlarged scale, is

a section on the line C—C Figure 1, showing the letter type pusher which limits the recoil of the pusher and the platform at its marginal edge.

Figure 5 is a section on the line D—D Figure 1, showing a section of part of the three platforms represented in Figure 1 and in marginal side view to the left of the slides or chutes, the mouths of the slides or chutes being represented by dotted lines.

Fig. 6 is an elevation from the right hand side of four push buttons showing their pivoted connections and the mounting of two release levers on the armature and of a wing. This view also shows a section of the two perforated plates.

Figure 7 is a front elevation of a push button and its articulated mounting.

Figure 8 is a front elevation of a wing carrying the two shafts with the blocks, the levers carrying the arms with their feet, the claws and the bevelled portions. This view also shows a section on the line E—E of the first platforms and an elevation of the marginal edges and the slots for the passage of the type.

Figure 8a shows a modified form of part of Figure 8. In this figure the blocks which actuate the levers so as to balance the push buttons are shown as being replaced by coiled springs.

Figure 9 is a plan showing a radius of the first platform and a radius of the second platform with the corresponding arms. The claws are shown in engagement with the type.

Figure 10 is a longitudinal section of a foot.

Figure 11 shows a plan and elevation of a spacing block.

Figure 12, drawn to an enlarged scale, shows a partial plan of the keyboard.

Figure 13 is a section on the line F—F Figure 1 showing the passage along which the letters pass into proper position in the line.

The type magazine is formed by a suitable number of superposed metal platforms or plates of decreasing area having the form of a truncated right angled triangle one side of which adjacent the right angle is arranged at the top, the hypotenuse of the triangle being arranged at the right hand side. The top platform is quite open; the others have three projecting sides.

Each platform is divided into regions by

horizontal bars *b* or strips of square section. To each region is allotted a letter or a sign.

At the hypotenuse side, each platform is provided with a marginal strip *c* which passes under the bars *b* below which is a space *d* (Figure 8) sufficient to allow of the passage of the type.

- The open part of each platform sidewise of the marginal strip forms a slide or chute on which the type arranged level thereon can slide in order to pass to a collector *e*. In passing to the collector *e* the type are swung about a corner from standing on edge to lying on the side and slide under the bars *b* and a type directed and guided through the passage or guideway *f* fall into correct position in the assembled line of type between the pusher *g* and the adjacent type or spacing block.
- The type pusher *g* is actuated by a to-and-fro movement by means of a cam wheel *g'* actuated by a belt or cord passing round a groove in a pulley *g''* and by a retracting spring *g'''* secured at one end at *g''* to the pusher and at the other end at *g''''* to a lower piece *g''''* which acts as a guide and limits the recoil.

By reason of the oblique position of the slides or chutes each row of type letters is inside those which are above and the same row projects over those which are below, in such manner that the types of all the regions when they are in situ or on place can pass by their slide or chute without encountering any obstacle.

In order to pass to the collector, the type from the platform which are above the first platform follow first of all the marginal strip *c* in their sliding movement, then, when they reach the end of this they strike against a strip *h* which causes them to change their direction of movement and the part *i* forming an extension of the slide or chute directs the type toward the collector and thence through the passage *f* in position in the line of type to be assembled.

The two first platforms are the bottom platforms. They contain the type most generally in use which forms approximately 95 per cent of the usual printed matter.

The other platforms contain type which are more or less seldom used. There is therefore very little, if any, use in assembling these type mechanically in view of the facility with which they can be positioned by hand in a chase. The number of platforms which is indefinite could be reduced in practice to 4, 3, or even to two only.

The keyboard is applied only to the first two platforms. It is provided with four rows of keys. The first and third rows of keys correspond to the second platform and the second and fourth rows of keys correspond to the first platform.

To the right of the aforesaid keyboard is

arranged a second keyboard which has only two rows of keys. This keyboard is herein-after referred to as the justifying keyboard which is usual in a magazine. The blocks for justifying have their special collector. These spacing blocks are necessary when the apparatus is combined with a justifying machine of the type described in my French Patent No. 521,182, dated 26th July 1920.

If the apparatus is not combined with a justifying machine, the spacing magazine is useless and justification is effected by hand as in the majority of movable type assembly or setting up machines as present in use.

The means for releasing a type as shown in the drawings comprises a key *j* carried by a rod which passes through a hole in a plate *l* which acts as a guide and a stop for the key. The rod is screwed into a socket *m* having a flat portion adapted to engage between the jaws of a forked lever *n* to which the socket *m* is pivotally connected. The lever *n* is secured on a shaft *o* having at its end a counterweight *p* or a spring *p'* to balance or to maintain the key in its up position. The block carries a lever *q* the upper end of which is articulated to an arm *r* which extends to the row of type in the magazine. Towards the end the arm *r* carries a block *s* having a quoin or wedge *s'* (Figure 9) which engages in the space *d* or slot which quoin or wedge *s'* yields to allow of the passage of the type. To the rear of the block the arm *r* carries a claw *s''* and the arm is bevelled at its end.

The weight of the blocks or the tension of the spring (Figure 8^a) acts to cause the releasing means to push the arm toward the row of type. When the bevelled end of the arm reaches the row of type the block *s* is raised and the claw stops at the first type against which the claw rests.

If now the key be operated, the block *s* is withdrawn from the type at the same time as the claw swings the type which served as a support. The type then slides under the bar *b* which held it and the type is directed towards the collector *e*. When the key is released the claw comes to bear on the succeeding type.

The keyboard with the releasing means is carried by an angle bracket *t* secured under the first platform. All the shafts *o* are supported at their front ends by angle brackets such as *t'* their other ends being supported in a frame *t*. Each angle bracket serves as a support for the ends of two shafts which are superposed. The upper shaft carries the corresponding parts for the second platform. Its position is determined by a ring *u* disposed inside the frame *t* and by the block *p* which is arranged inside the angle bracket. The lower shaft carries the corresponding parts for the first platform. The position of the lower shaft is determined by

a ring u' which is placed inside the frame t and by the block p situated to the rear of the angle bracket.

In order that the justifying blocks may offer a resistance to the thrust of the blocks, blocks or wedges v are employed which serve as supports. These blocks are each provided on the lower face with a stud v' adapted to engage in a hole v^2 in one or other of a number of holes in the regional platform.

When the types in front of the slots in any of the rows are exhausted, the remaining types are pushed forward so as to begin again. The blocks s recoil under the thrust but they must not touch the marginal strip of the slide or chute. There ought to be sufficient space to permit of the passage of the type which are above and also in order that they can recoil when the corresponding key is operated.

In order to stop the blocks at any suitable distance from the marginal edge of the chute or slide, a plate l is provided having holes which act to guide the rods carrying the keys, a further plate l' having holes of larger diameter is also provided the holes in the plate l' being concentric with the holes in the plate l . When assembling the holes are concentric so that the bases of the keys when depressed can descend to the plate l and the blocks can recoil to the marginal edge of the slides or chutes. But, when it is desired to push the type the plate l' is slid so that the holes of a larger diameter are tangential interiorly with the small rods so as to prevent the base of the keys from reaching the plate l and stop-blocks before they touch the edges of the slides or chutes.

The two plates provided with holes are only shown in Figures 1 and 12.

Having now particularly described and ascertained the nature of my said invention and in what manner the same is to be performed, I declare that what I claim is:

1. Printing type assembly or composing apparatus characterized by type magazine comprising two superposed platforms inclined at 45° and supported on a base, the said platforms being divided by horizontal bars so as to form spaces for the type the bottom of the type being supported on the horizontal bars so that the types are ready to hand, the said bars being provided with

a space adjacent the slides or chutes which lead to a collector, a space or slot sufficient to allow of the passage of the flat type on their release by mechanism, actuated by keys from a keyboard or by hand.

2. Printing type assembly or composing apparatus having justifying spaces juxtaposed adjacent the type magazine and formed by a single platform divided into spaces by horizontal bars which act to support the bottoms of the spacing blocks so that the latter are ready to hand, the rows of spacing blocks being supported on blocks movable in the spaces in order to resist the action of the releasing mechanism which is used to effect position of the spacing blocks under the action of keys on a keyboard so that the said spacing blocks can slide in the spaces or slots below the horizontal bars, then thereafter fall into a special collector.

3. Printing type assembly or composing apparatus comprising a releasing mechanism and a keyboard provided with keys connected to shafts which actuate levers articulated to arms projecting to the rows of type contained in a type magazine, the said arms carrying claws and having bevelled lifting ends and stop-blocks, the claws always resting under the action of a spring on the first type of a row in the magazine and by the action of a key causing the said type to be held in position between the claws and the stop-block so that the type can be rotated into position to enable it to descend into the line in which the type is to be assembled.

4. In printing type setting apparatus, a magazine, a collector having a channel formed by the slide of the magazine, with an inclined plane and ribs which cause the type to pass through a channel in which they fall and in which they are straightened out before being inserted between the letter pusher and the line to be composed.

5. Printing type assembly or composing apparatus in accordance with claim 1 having a type pusher actuated in a to-and-fro movement by means of a cam wheel driven by a belt, cord or equivalent and a retracting spring fixed at one end to the pusher and at the other end to an intermediate piece so as to limit the recoil.

In witness whereof I affix my signature.

ALFRED LUBAC.
